VAPOR-ELECTRIC DEVICE AND METHOD OF
MAKING THE SAME

Gerhard Lewin, Maplewood, and Ernest A. Goldman, Bloomfield, N. J., assignors to Westinghouse Electric Corporation, East Pittsburgh, Pa., a corporation of Pennsylvania

Application September 12, 1951, Serial No. 246,296

5 Claims. (Cl. 313—328)

1

This invention relates to vapor-electric devices, such as are generally known as ignitrons.

A recent development in this art is the provision of a sponge cathode consisting of a material of porous character which will absorb mercury or the like and constantly present a mercury-wet surface toward the ignitor and anode in an ignitron. In the usual mercury-pool type of ignitron, the ignitor penetrates below the surface of the pool and thus insures conductive contact between the ignitor and mercury. In the ignitrons with a sponge cathode, however, the contact between the sponge and ignitor is one of engagement of the end of the ignitor on the sponge surface. It has been found necessary to apply pressure on the ignitor toward the cathode to assure conductive contact at the point of engagement. The present invention contemplates an assured contact of ignitor and sponge cathode.

An object of the invention is to assure such contact without resort to spring pressure or weights.

Another object of the invention is to provide constant and unalterable contact of ignitor and cathode.

A further object of the invention is to fabricate the cathode and ignitor with predetermined area of contact.

A still further object of the invention is to provide an ignitor embedded in the sponge cathode during fabrication and permanently fixed thereto.

Other objects of the invention will appear to those skilled in the art to which the invention appertains as the description proceeds, both by direct reference thereto and by implication from the contact.

Referring to the accompanying drawing, in which like numerals of reference indicate similar parts throughout the several views:

Fig. 1 is a vertical central sectional view of an arbitrarily selected ignitron showing our invention included therein.

Fig. 2 is a view showing the cathode and the igniter in cross section.

In the specific embodiment of the invention and associated ignitron construction illustrated in the drawing, there is shown a cylindrical casing 10 of steel or other sturdy material having a bottom 12 integral therewith and a top header 13 sealed at the upper rim of said casing to provide a closed envelope adapted to be evacuated.

The header provides appropriate lead-in seals 55

2

14, 15 for electrode leads 16, 17 respectively for an anode 18 and ignitor 19 within the casing. The lead-in seals each include a glass or other insulating sleeve 20 by which the leads are kept electrically distinct from each other and from the casing. The anode 18 is located toward the top of the casing, well above the bottom wall 12, whereas the ignitor 19 is located below the anode and is directed toward and terminates at its bottom in the vicinity of said bottom wall.

In said casing 10, at the bottom thereof juxtaposed on the bottom wall 12, we provide a cake or body 21 composed of a porous material which has the property of a sponge absorptive and/or adsorptive to mercury or other reconstructable liquid cathode material, and while we prefer to use metal for the purpose, we do not confine ourselves thereto. Such metals as sintered iron, sintered molybdenum, sintered ruthenium, sintered platinum and the like, singly or in any combination thereof, have been found to be acceptable cathode sponge materials. The cake or sponge 21 is flat and occupies only a small part of the casing, and preferably diametrically extends across the bottom of the casing or envelope to the cylindrical wall thereof with which it may make frictional engagement for retention in place.

Mercury or other reconstructable cathode material is applied to the sponge body 21 to extent that said body will absorb the mercury or the like without any excess remaining on the surface. One manner of thus charging the sponge body with mercury is to cleanse the sponge material until sufficiently clean to be wetted by mercury and then apply an excessive amount of mercury in the casing, whereupon the sponge will immediately fill with mercury, after which the free mercury which is not absorbed into the sponge can be poured off. The sponge body or cake 21 with the absorbed mercury constitutes the cathode of the ignitron.

The principal feature of the present invention is the unification of sponge body 21 and ignitor 19 so that the ignitor has fixed position and positive engagement with the sponge body. The preferred accomplishment of this desideratum is to bury the lower end of the ignitor in said sponge body with the major portion of the ignitor projecting perpendicularly upward from the top surface of said body. It is furthermore preferred that the ignitor have inseparable engagement with the sponge body and thereby assure good electrical contact of a considerable surface of the ignitor with the cathode. One mode of ac-

complishment of this assembly is to shrink the sponge body or cake onto the marginal end portion of the ignitor.

In practice, the sponge body is fabricated by compressing a predetermined volume of granular or otherwise prepared material of multitudinous particles or units into a cake formation which is sintered in the compressed shape and constitutes a firm, porous body in consequence of the initial material used and treatment thus applied. A pressure of one to two tons per square inch and sintering temperature of approximately 1800° F. have proven satisfactory with particles of iron and other materials hereinbefore listed. As an example of means for compressing the multitudinous particles or units into cake formation, Figs. 3 and 4 show a hollow die 22 the inside diameter of which is made to correspond, with compensation for shrinkage, to the desired diameter of the cathode body to be formed. The bottom end of the hollow die is closed by a sectional lower die 23, and an upper die 24 is provided adapted to be lowered into the hollow die for applying the desired pressure to material 25 poured or otherwise introduced into the hollow die. The lower die 23 has a properly located socket 26 therein for reception of a preformed ignitor 19. The socket is of appropriate depth to receive the major portion of the ignitor which is placed in said socket upside down so that what is normally the bottom end of the ignitor in use protrudes upwardly from the top surface of the lower die. The amount of protrusion is made to agree with the desired depth of ultimate burial of the ignitor in the cathode sponge body.

The method of fabrication herein disclosed contemplates first introducing a small amount of cushioning material 27 in the bottom of socket 26 having the two-fold functions of conforming the bottom of the socket to the surface configuration of the ignitor end to prevent cracking or shearing the ignitor when pressure is applied, and to also prevent the ignitor from sticking to the bottom of the socket as a result of applied pressure. The amount of protrusion of the ignitor can be varied by appropriate variation of amount of material 27 introduced into socket 26. While numerous materials are usable for forming the cushion, it is convenient to utilize a small quantity of the same material of which the sponge cathode is to be composed, and thus avoid possible contamination of the ignitor by introduction of some deleterious ingredient.

After the cushioning material 27 is introduced into socket 26, the ignitor 19 is inserted, top end downward into contact with the cushioning material and with the other end protruding above

the top face of the lower die. Next a measured amount of sponge-forming material 25 such as finely divided iron, molybdenum and so forth as above described, is introduced into the hollow die on top of the lower die and completely surrounds and covers the protruding end of the ignitor. Then the top die is forced down under the desired pressure of one or two tons per square inch thereby compressing material 25 into a compact, though spongy, firm cake with an end of the ignitor embedded therein. This cake, with the ignitor therein, is then sintered at approximately 1800° F. The formed cake is removed from the dies with the embedded ignitor therewith, before sintering. Due to the compression applied to the material in forming the cake, the ignitor is tightly gripped therein. The sintering operation obtains some shrinkage of the cake and consequently the ignitor is even more tenaciously anchored in the cake or sponge body in the completed assembly, and thus the ignitor is permanently attached to and has an end buried in the sponge body.

It may be noted, that the preferred construction of ignitor utilizes an integral carbon head or upper end portion 29 which is more readily bored with a hole 30 for reception of the lead-in rod 17 than the usual ignitor, which, for sponge cathode use may consist of boron carbide and alumina.

We claim:

1. In combination, a porous cathode body, and an ignitor secured to said body.
2. In combination, a porous cathode body, and an ignitor having an end embedded in said body in tight contact therewith.
3. In combination, a porous cathode body, and an ignitor having an end embedded permanently in and gripped by said body.
4. A method of manufacture of a combined cathode and ignitor comprising preforming an ignitor and simultaneously compressing other material around an end margin of said ignitor and into its ultimate shape of cathode body.
5. A method of manufacture of a combined cathode and ignitor comprising preforming an ignitor and simultaneously compressing other material around an end margin of said ignitor and into its ultimate shape of cathode body, and thereafter sintering the said body with the ignitor buried at its end therein, thereby both conditioning the body for use and shrinking it into tight engagement with the ignitor.
